UNITED STATES PATENT OFFICE

171,039

SLICING AID

Robert V. Loeb, Los Angeles, Calif.

Application June 8, 1953, Serial No. 25,361

Term of patent 3½ years

(Cl. D44—29)

To all whom it may concern:

Be it known that I, Robert V. Loeb, have invented a new, original, and ornamental Design for a Slicing Aid, of which the following is a specification, reference being had to the accompanying drawing, forming a part hereof.

Fig. 1 is a perspective view of a slicing aid, showing my new design;

Fig. 2 is a side elevational view thereof; and

Fig. 3 is a front elevational view thereof.

I claim:

The ornamental design for a slicing aid, as shown.

ROBERT V. LOEB.
